US00D912722S

(12) **United States Design Patent** (10) **Patent No.:** **US D912,722 S**
(45) **Date of Patent:** **** Mar. 9, 2021**

- (54) **SNAP-IN NOSE PADS FOR EYEWEAR**
(71) Applicant: **Roka Sports, Inc.**, Austin, TX (US)
(72) Inventors: **Robert Canales**, Austin, TX (US); **Kurt Spenser**, Burbank, CA (US); **Tobin Rohrbach**, Trabuco Canyon, CA (US); **James Oman**, Austin, TX (US); **David Ginther**, Ladera Ranch, CA (US); **John Currie**, Orange, CA (US); **Steven Oldham**, Corona, CA (US); **Eric Suburu**, Tustin, CA (US); **Mark Niiro**, Dallas, TX (US); **Tet Kawakami**, Austin, TX (US)
(73) Assignee: **Roka Sports, Inc.**, Austin, TX (US)
(**) Term: **15 Years**
(21) Appl. No.: **29/643,342**
(22) Filed: **Apr. 6, 2018**
(51) LOC (13) Cl. **16-06**
(52) U.S. Cl. **D16/333**
(58) **Field of Classification Search**
